CORNER STIFFENING AND LEG HOLDING
CONSTRUCTION FOR COLLAPSIBLE ME-
TALLIC TWIN TUBSWilliam C. Welforth, Flint, Mich., assignor to
Durand Metal Products Corporation, Saginaw,
Mich., a corporation of Michigan.

Application April 1, 1949, Serial No. 84,982

4 Claims. (Cl. 220—73)

1

This invention relates in general to a construction for stiffening the corner of a rectangular metallic container having corner legs and a rolled rim, and for holding the upper end of one of said corner legs against said container; said construction comprising a stiffening device securable to said rolled rim at a corner thereof and a suitably arranged flange on the upper end of each of said legs for interengagement with said stiffening device.

Persons acquainted with the manufacture and assembly of metallic containers, such as those supported upon legs and having a rolled rim along the upper edges thereof, have recognized the need for a sturdy, neat, inexpensive construction, including a device securable to said rim at the corners thereof, for imparting rigidity to said rim as well as to the container.

In order to conserve space when shipping metal containers having legs, such as twin laundry tubs, the legs thereof are generally removed from said tubs before they are packed for shipment. However, primarily as a matter of economy, much of the rigidity in this type of metal container is often derived from having the legs in their assembled positions with respect to the container. Therefore, shipment of the dismantled containers, and/or assembly of the legs upon said containers, especially by unskilled persons, has been made difficult by the flimsy and unsturdy condition of the container prior to its assembly with its legs. Furthermore, this flimsy and unsturdy condition of the container, prior to assembly with its legs, also effects a bad impression upon persons receiving the container.

The flimsiness and unsturdiness in the structure of such a container generally arise from the fact that the rolled rim cannot be economically fabricated to extend around the corners of the container. Thus, until such time as the legs can be assembled to the said container, it is both flimsy and unsightly.

Accordingly, a primary object of this invention is the provision of a device for stiffening the corner of a rectangular, metallic container having a rolled rim, said device being securable to said rim at the corners thereof.

A further object of this invention is the provision of a stiffening device, as aforesaid, for imparting rigidity to a rectangular, metallic container having a rolled rim comprised of a plurality of individual elements extending between the corners of said container, said device being securable to the adjacent ends of a pair of adjacent rim elements.

2

A further object of this invention is the provision of a corner stiffening device, as aforesaid, for removably engaging and securely holding the upper end of a corner leg.

5 A further object of this invention is the provision of a corner stiffening device, as aforesaid, which is amply sturdy in structure, neat in appearance and inexpensive, both to fabricate and install.

10 Other objects and purposes of this invention will become apparent to persons familiar with this type of equipment upon referring to the accompanying drawings and upon reading the following specification.

15 In meeting those objects and purposes heretofore mentioned, as well as others incidental thereto and associated therewith, I have provided a substantially L-shaped channel member whose flanges extend perpendicularly from the plane

20 defined by said L. Thus, one flange of the channel member is on the inside of the curve in said L, which curve is advantageously arcuate, whereas the other flange of the channel member is on the outside of the said curve. When the channel member is assembled on the corner of the rolled rim of a metal container the web of the channel

25 rests on the top of the rim and the flanges of the channel snugly embrace the inner and outer sides of the rim. An integral lip is provided on the lower, free edge of the outer flange along the curved portion thereof, said lip extending toward the inner flange for the purpose of engaging the upper, outwardly flanged end of a corner leg.

30 A pair of gripping flanges integral with the free edge of the outer flange, adjacent to the opposite ends thereof, extend therefrom toward the said inner flange for engaging the adjacent ends of two adjacent elements of the rolled rim on the metallic container.

35 40 For the purpose of convenience in description, the terms "inwardly" and "outwardly," as used in the description of both the corner stiffening device and the leg construction to which this invention relates, shall be understood to mean toward and away from, respectively, the geometric center of the rectangular container with which

45 said stiffening device and leg construction are used. The terms "upper" and "lower" shall be understood to refer to the device when positioned in its normal manner of use.

50 For illustrations of a particular, preferred embodiment of the invention, reference is made to the accompanying drawings in which:

Figure 1 is a perspective view of a rectangular metallic container provided with a plurality of

the corner stiffening devices, included within this invention, with corner legs secured thereto.

Figure 2 is a sectional view as taken along the line II-II of Figure 1.

Figure 3 is a sectional view substantially as taken along the line II-II of Figure 1, with the leg removed.

Figure 4 is a sectional view taken along the line IV-IV of Figure 2.

Figure 5 is a sectional view taken along the line V-V of Figure 2, showing a portion of the upper edge of the container and a corner stiffening device secured thereto in the inverted position.

Figure 6 is a broken view of the inside of a corner of the rectangular container and rolled rim thereof with a stiffening device secured thereto.

Construction

As shown in Figure 1, the corner stiffening device 10 is designed, in this embodiment of the invention, for cooperation with and securement to the rolled rim 11 of a rectangular, metallic container, such as the twin laundry tubs 12. The tubs 12 are provided with four substantially identical corner legs 13 having L-shaped cross-sections to facilitate engagement between each of said legs and a corner of said tubs. An outwardly extending support flange 14 is provided at the upper end of said leg for appropriate engagement by said stiffening device 10 (Figures 2 and 5), as hereinafter described in detail. Appropriate bracing 15 is provided between the legs 13 beneath the tubs 12 for holding them against movement away from each other and away from the tubs.

The four stiffening devices 10, shown at the four corners of the tubs 12 in this embodiment of the invention, are preferably identical. Therefore, since the legs 13 are also identical, a detailed description will be given of the structure and relationship between one corner stiffening device and the leg cooperating therewith, and such description will be understood to apply to the structure of and relationship between the other corner stiffening devices and their corresponding legs.

It will become apparent that my corner stiffening device 10 is applicable to use with practically any type of rectangular, metallic container having a substantially cylindrical rolled rim regardless of whether said rim is integral with, or separably securable to, the upper edge of the container. However, in the particular embodiment of the invention herein described, it will be assumed that the rolled rim 11 is separably secured to the upper free edge 16 of the twin tubs 12 and is fabricated substantially as disclosed in a pending application Serial No. 21,489, filed April 16, 1948, now Patent No. 2,539,141. Accordingly, the rolled rim 11 has a pair of adjacent rim elements 17 and 18, having adjacent, spaced ends 21 and 22. The rim element 17 is secured to the upper edge of the tub sidewall 23 whereas the rim element 18 is secured to the upper edge of the tub end wall 24.

The corner stiffening device 10 (Figures 2, 4, 5 and 6) is comprised of an L-shaped channel member 25 with a substantially semi-circular cross-section. The bend in said channel member 25, which is preferably arcuate and midway between the ends 29 and 31 of said channel member, is preferably so arranged that one flange 27 is on the inside of the curve and the other flange 28 is on the outside of the curve. Thus, the inner and outer flanges 27 and 28 respectively, extend

from the arcuate web 26 perpendicularly to the plane defined by said L. The substantially straight end portions 29 and 31 are perpendicularly disposed to each other.

The radius of curvature of the web 26 in the channel member 25 is preferably such that said channel member will snugly embrace the adjacent ends 21 and 22 of the rim elements 17 and 18 when the stiffening device 10 is operably placed upon a corner of the rolled rim 11. Since, in this embodiment of the invention, the cylindrical rolled rim 11 is substantially tangent to the tub sidewall 23 and end wall 24, the inner flange 27 (Figure 6) of the stiffening device 10 extends below the rim 11 and bears snugly against the said tub sidewall and end wall.

A pair of rim gripping flanges 32 and 33 (Figures 2 and 3), which are preferably but not necessarily integral with the free lower edge 34 of the outer flange 28 at the ends 29 and 31 thereof, extend therefrom toward the corresponding ends of the inner flange 27. The said gripping flanges 32 and 33 snugly embrace the ends 21 and 22 of the rim elements 17 and 18, respectively, thereby securing the corner stiffening device 10 to the rolled rim 11 at the corner thereof.

An integral lip flange 35 is preferably integral with and extends inwardly from the free edge 34 of the outer flange 28 along the curved portion thereof intermediate the end portions 29 and 31. The inward and lengthwise extents of the lip flange 35 are primarily governed by the outward extent of the support flange 14 at the top of the corner leg 13. The distance between the lip flange 35 and the web 26 is governed by the diameter of the rolled rim 11 and the thickness of the support flange 14, which bears against the rim 11 when the leg 13, thereof, is vertically positioned along the corner of the tubs. The said support flange 14, which may be relieved at 36 and 37 (Figure 2) to facilitate fabrication, preferably extends perpendicularly outwardly (Figure 4) from the upper end of the corner leg 13 and is curved slightly upwardly to snugly embrace the lower side of the rolled rim 11. Thus, the flange 14 is snugly receivable between the lip 35 and the rim 11, when the leg 13 is in operating position, and the adjacent ends 21 and 22 of the rim elements 17 and 18 are supported upon the said flange 14, thereby supporting the tubs 12.

A sealing flange 38 (Figures 2 and 3) may be provided on the free edge 39 of the inner flange 27 along the curved portion thereof extending outwardly therefrom toward the outer flange 28 in order to fill the opening between the said curved portion of the inner flange 27 and the adjacent portions of the sidewall 23 and end wall 24.

Assembly

The corner stiffening device 10 is advantageously fabricated with the gripping flanges 32 and 33 substantially parallel with the corresponding ends of the inner flange 27, as shown at 32a in Figure 4. The stiffening device 10 is urged downwardly over the adjacent ends 21 and 22 of the rim elements 17 and 18 until the web 26 snugly engages said rim elements 17 and 18, and said inner and outer flanges 27 and 28, respectively, embrace the opposite sides of said rim adjacent to the ends 21 and 22. The gripping flanges 32 and 33 are then urged snugly around the lower sides of the rim elements 17 and 18 thereby securing the stiffening device 10 upon the rolled rim 11.

When it becomes desirable to assemble the cor-

ner legs 13 upon the tubs 12, the support flange 14 of a particular leg is inserted between the lip flange 35 and the lower surfaces of the adjacent ends 21 and 22 of the rim elements 17 and 18 by positioning the leg 13 at an angle with respect to the appropriate corner of the laundry tubs. In such position the corner leg 13 is spaced from the bottom of the tubs 12 whereas the upper end of the leg 13 is bearing against the upper edge 16 of the tub. When the support flange 14 slips over the top of the lip flange 35, the lower end of the corner leg 13 is urged toward the tubs until said leg snugly engages the corner of the tub and is in a substantially vertical position. When the leg is in this position, the support flange 14 is held snugly and substantially immovably between the lip flange 35 and the lower sides of the adjacent ends of the rim elements 17 and 18. The bracing 15 may then be secured to the legs 13 beneath the tubs 12, thereby preventing the legs from moving away from said tubs. Thus, it will be seen in Figures 4 and 5 that the support flange 14 bears upwardly against the rolled rim 11 whereas it is prevented from moving downwardly away from said rolled rim by the lip flange 35 as long as the leg is held firmly against the tubs. Accordingly, by merely providing any suitable convenient means, such as the bracing 15, for preventing the spreading apart of the lower ends of the legs 13, said legs are held firmly against said tubs.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claims.

I claim:

1. In a device for stiffening a corner of a rectangular container having a leg embracing said corner with an outwardly extending support flange at the top thereof, said container having a tubular rim extending outwardly from said container and supported upon said support flange, the combination comprising: a curved channel having inner and outer downwardly extending flanges adapted for snugly embracing said rim; means for securing said channel on top of said rim at a corner of said container; and a lip on the lower edge of said outer flange intermediate the ends of said channel, said lip extending toward said inner flange under the support flange on said leg for holding said support flange against said rim.

2. In a device for stiffening a corner of a rectangular container having a leg embracing said corner with an outwardly extending support flange at the top thereof, said container having a tubular rim extending outwardly from said container and supported upon said support flange, the combination comprising: a curved channel having inner and outer downwardly extending flanges snugly embracing said rim; a pair of spaced gripping flanges secured to the lower edge of said outer flange and extending toward said inner flange beneath and tightly against said rim; and a lip on the lower edge of said outer flange intermediate said gripping flanges, said lip extending toward said inner flanges under the

support flange on said leg for holding said support flange against said rim.

3. In a device for stiffening a corner of a rectangular container having a leg extending vertically along and embracing said corner, said leg having an outwardly extending support flange at the top thereof, and said container having a molded rim extending outwardly from said container and comprised of cylindrical elements secured to the upper edge of said container and extending between the corners thereof, the adjacent ends of the rim elements bearing upon said support flange, the combination comprising: an L-shaped channel having a U-shaped cross-section with inner and outer downwardly extending edges, said channel snugly embracing the top and sides of the adjacent end portions of two of said rim elements; a pair of gripping flanges secured to the opposite ends of said outer edge and extending toward said inner edge beneath and tightly against said rim; a leg flange secured to said outer edge, intermediate said gripping flanges, and extending therefrom toward said inner edge under said support flange for holding said support flange against said rim elements and the upper end of said leg against said container.
4. In a device for stiffening a corner of a rectangular container having a leg extending vertically along and embracing said corner, said leg having an outwardly extending support flange at the top thereof, and said container having a molded rim extending outwardly from said container and comprised of cylindrical elements secured to the upper edge of said container and extending between the corners thereof, the adjacent ends of the rim elements being spaced from each other and bearing upon said support flange, the combination comprising: an L-shaped member having a semi-circular cross-section with inner and outer downwardly extending edges, the opposite ends of said member overlapping and snugly embracing the adjacent end portions of two of said rim elements; a pair of gripping flanges integral with the opposite ends of said outer edge, one flange extending toward said inner edge beneath and tightly against each of said elements; a leg flange integral with the said outer edge midway between said gripping flanges, and extending therefrom toward said inner edge under the support flange on said leg for holding said support flange against said rim elements and the upper end of said leg against said container.

55 WILLIAM C. WOLFORTH.
